UNITED STATES PATENT OFFICE

EMIL C. LOETSCHER, OF DUBUQUE, IOWA

SLIDING STAIRWAY

Application filed January 21, 1928. Serial No. 248,515.

This invention relates to improvements in stairways, and particularly to stairways of the type which move through a hatch in a ceiling.

5 It has heretofore been proposed to provide a ceiling hatch with a downwardly swinging hinged door or panel, and to slidably mount on this doorway, a stairway which may be concealed above the ceiling when it is not in 10 use.

The primary object of the present invention is to simplify the construction of such devices, and to provide a much more inexpensive structure.

15 A further object of the invention is to furnish in such a device, simple inexpensive means for assisting in raising the stairway and to retard the lowering of the latter.

A still further object is to provide a combination of this type, including a novel braking mechanism which cooperates with the stairway to retard the downward movement of the latter.

Another object is to provide a stairway of 25 the character which moves through a hatchway in a ceiling, with a hinged section that may be folded against the main part of the stairway, when the latter is to be stored.

With the foregoing objects outlined and 30 with other objects in view which will appear as the description proceeds, my invention consists in the novel features hereinafter described in detail, illustrated in the accompanying drawings, and more particularly 35 pointed out in the appended claims.

Referring to the drawings,

Fig. 1 is a side view of my improved device with the stairway in lower position.

Fig. 2 is a front view of the same.

40 Fig. 3 is a view similar to Fig. 1, but showing the stairway in its uppermost position above the ceiling.

Fig. 4 is an enlarged plan view of the braking mechanism and a portion of the door.

45 Fig. 5 is a detail sectional view of one side of the stairway showing the means for latching the hinged section of the stairway to the remainder of the latter when the hinged section is folded.

50 In the drawings, 1 designates a ceiling hav-

ing a hatch opening 2, adapted to be closed by a swinging door or panel 3, which is hinged to the doorway at 4.

Brackets 5 are fixed to the panel and preferably arranged at the corner portions of the latter, and each of these brackets carries a roller 6, which may be mounted on a ball bearing.

The stairway 7 is preferably formed of stringers 8 and treads 9, and each stringer 60 consists of a pair of bars spaced apart to provide a longitudinal slot or guideway 10 in which the rollers 6 operate. Stops 11 and 12 are arranged at the ends of the guideway, and the stairway is preferably provided with 65 a hand rail 13.

The stairway may readily slide up and down on the rollers 6, and in order to retard the downward movement, the following mechanism is provided. A drum 14 is fixed 70 to a shaft 15, journaled in roller bearings or the like 16, carried by brackets 17 that are secured to an intermediate portion of the panel 3. A rope or cable 18 has one of its 75 ends fixed to one of the lower treads of the stairway by any suitable fastening means, such as a screw-eye 19. This rope or cable is wrapped around the drum a few times, as shown at 20, and its other end is connected to one end of a coiled spring 22, the other end 80 of the coiled spring being connected by any suitable adjusting means, such as turn-buckle 23, to one of the upper treads of the stairway. The spring 22 always keeps the rope 18 taut, so that the rope compels the rotation of the 85 drum when the stairway is either raised or lowered.

I have combined with the drum, simple and inexpensive means for retarding the rotation of the drum when the stairway moves downwardly, but which does not interfere with the rotation of the drum when the stairway moves upwardly. Such means comprises a second rope or cable 24, wrapped around the drum for a few turns, as shown at 25. One end of 90 this rope is tied at 26 to a screw-eye or the like that is fixed to the panel 3, and the other end of the cord is connected to a coiled spring 27, which is connected to an eye-bolt 28 extending through a screw-eye 29 on the panel 100.

and provided with a thumb nut 30 for adjusting purposes.

Due to this construction, when the drum moves in a clock-wise direction, owing to the movement of the stairway downwardly the 5 spring 27 will tend to bind the rope on the drum, and retard its movement, and consequently, the movement of the stairway downwardly will also be retarded, as the rope 18 10 cannot move as rapidly as it might if there was no brake on the drum.

On the other hand, when the stairway is moved upwardly, the rope 18 will turn the drum in a counter-clockwise direction, and this will cause the spring 27 to stretch and 15 loosen the rope 24 to such extent that the brake will not interfere with the operation of the drum.

In the operation of the device, it will be 20 assumed that the parts are in the position shown in Fig. 3, that is, with the stairway above the ceiling 1. At such time, the overhanging weight of the stairway will tend to keep the panel closed, but in addition to this, 25 I have provided special means for closing the panel and for retaining it in closed position. Such means includes coiled springs 31 mounted at opposite sides of the stairway. Each of these springs has its upper end fixed 30 to the doorway at 32, and its other end connected to an eye-bolt 33 (similar to 28) and provided with a thumb nut 34 similar to 30 which bears against a screw eye 35 fixed to the panel. By adjusting the thumb nut 34, 35 the tension of the spring may be varied.

With the parts above the ceiling, the operator can move the same into the position shown in Fig. 1, by first pulling downwardly on the suspended cord 36. This causes the 40 panel to swing on its hinges, and brings the lower end of the stairway into a position where it can be grasped by the operator. The operator can then pull the stairway downwardly, and this movement will be retarded 45 by the braking mechanism.

When it is desired to return the stairway to its concealed position, the operator simply lifts upwardly on the stairway, and when he has moved it high enough, its overhanging 50 weight, together with the springs 31, will return the parts to the position shown in Fig. 3.

By properly adjusting the springs through the medium of the turnbuckle 23 and the thumb nut 30, the operation can be varied somewhat, and the spring 27 may be so adjusted that the stairway will move down at any speed desired, or the stairway will remain in any position, regardless of the angle of the stairway. Furthermore, by a suitable 60 adjustment, the stairway will slowly move downward under its own weight, and the friction on the drum can be just sufficient to almost counter-act the effect of gravity.

When the stairway is moved to the uppermost position, there is almost sufficient counter-

balance weight in the overhanging portion of the stairway to raise it to the upper closed position. However, with different ceiling heights, this may not always be the case. Therefore, the springs 31 are provided to furnish sufficient tension to balance the panel and stairway in any position.

The lower end of the stairway is preferably formed by a movable or folding section 8^a which is hinged at 8^b to the main portion of the stairway. When the section 8^a is folded, it will be engaged by spring clips 8^c, which will hold the same in folded position, as shown in Fig. 3.

From the foregoing, it is believed that the 80 construction, operation and advantages of the invention may be readily understood, and I am aware that changes may be made in the details disclosed, without departing from the spirit of the invention as expressed in the 85 claims.

What I claim and desire to secure by Letters Patent is:

1. The combination with a movable door, and a stairway slidably mounted on the same, of a brake drum, means operatively connecting the stairway to the brake drum for rotating the latter in opposite directions, when the stairway moves upwardly or downwardly, and means for retarding the movement of the 95 brake drum when the stairway is moved in one direction, said retarding means having no effect on the brake drum when the stairway is moved in the opposite direction.

2. The combination with a movable door, and a stairway slidably mounted on the same, of a brake drum, means operatively connecting the stairway to the brake drum for causing the latter to rotate in opposite directions when the stairway moves upwardly or downwardly, 100 a tension device for said means, and means for retarding the movement of the brake drum when the stairway is moved in one direction, said retarding means having no effect on the brake drum when the stairway is 110 moved in the opposite direction.

3. The combination with a movable door and a stairway movably mounted on the same, of a brake drum, means operatively connecting the brake drum to the stairway for causing 115 the brake drum to rotate in opposite directions when the stairway is moved upwardly or downwardly, a tension device for said means, a device for adjusting the tension device, and retarding means connected to the 120 brake drum for retarding the movement of the latter in one direction only.

4. The combination with a movable door having a stairway movably mounted thereon, of a brake drum, a flexible element passing about the brake drum and having its ends connected to the end portions of the stairway, resilient means forming part of said element for maintaining the element taut, and retarding means engaging the drum for retarding the 130

- movement of the drum in one direction only.
5. The combination with a swinging door having a stairway slidably mounted thereon, of a rotatable drum carried by the door, a flexible element wound about the drum and having its ends connected to the end portions of the stairway, means for maintaining said element taut, and a brake cooperating with said drum.
- 10 6. The combination with a swinging door and a stairway slidably thereon, of a brake drum, means operatively connecting the stairway to the drum for causing the latter to rotate in opposite directions when the stairway is moved upwardly or downwardly, a brake rope wound about the drum and having one of its ends fixed at a point adjacent the drum, and resilient means for tensioning the other end of said brake rope.
- 15 7. The combination with a hinged door and a stairway slidably mounted thereon, of a drum rotatably mounted on the door, means operatively connecting the stairway to the drum for causing the latter to rotate when the stairway is moved, a brake rope wound about the drum, means for fixing one end of the brake rope to said door, and adjustable resilient means for connecting the other end of the rope to the door.
- 20 8. In combination, a hinged door for closing a ceiling doorway, brackets carried by the door, a stairway slidably mounted on said brackets, a brake drum rotatably mounted on the door, a flexible element passing about the brake drum, and having its end connected to the end portions of the stairway, resilient means forming part of said flexible element for maintaining the latter taut, a brake rope wound about the drum, means for fixing one end of the brake rope to the door, and adjustable resilient means connecting the other end of the brake rope to the door.
- 25 9. In combination, a movable door for closing a ceiling doorway, a stairway mounted to move through said doorway, said stairway including a hinged section at its lower end portion adapted to be folded against the under side of the remainder of the stairway, and means for holding said section in its folded position.
- 30 50 In testimony whereof I affix my signature.
EMIL C. LOETSCHER.
